UNITED STATES PATENT OFFICE.

WILLIAM S. HADAWAY, JR., OF NEW ROCHELLE, NEW YORK, ASSIGNOR TO THE TEXAS COMPANY, OF NEW YORK, N. Y., A CORPORATION OF TEXAS.

TREATING HYDROCARBONS.

Application filed September 15, 1923. Serial No. 662,820.

This invention relates to the conversion of higher boiling hydrocarbons into lower boiling hydrocarbons, such as gasoline and other similar products.

5 The invention is particularly adapted for a method of treating hydrocarbon oils in which the oil is passed through a coil or equivalent heating means and the heated oil then discharged into an enlarged chamber 10 and has special reference to a system in which the bulk of the heat required is supplied to the oil before it reaches the enlarged chamber.

It is desirable to impart to the oil the 15 bulk of the heat required in the preliminary heating stage and to employ comparatively little or no external heating in the enlarged chamber where cracking takes place, since the application of heat to the metallic walls 20 of a chamber where decomposition occurs tends to the formation of carbon deposits on the walls of the vessel. In this type of operation, therefore, the heat required is maintained largely by the stream of heated oil 25 which is discharged thereinto and in order to maintain the contents of the cracking chamber at the desired temperature, it is desirable to thoroughly diffuse the stream of heated oil within the mass of oil in the 30 vessel. The present invention seeks to accomplish this result by bringing the heated oil into intimate contact with as many portions of the body of oil in the cracking chamber as is possible and in the least time.

35 In accordance with the invention, therefore, the oil after having been preliminarily heated to the desired temperature is discharged into the cracking chamber at a multiplicity of points and so dispersed therein 40 that the heated oil is thoroughly commingled and diffused with the mass of oil in the chamber, thus operating to maintain the required temperature throughout the contents of the chamber. In order to assist in the 45 diffusion of the oil charged with the mass of oil in the cracking vessel agitating means is employed and in a preferred embodiment of the invention, the preheated oil is discharged into the mass of oil in the cracking 50 vessel through movable spraying means which operate to carry on agitation of the contents and discharge streams or sprays of oil into the mass in the vessel.

For the purpose of describing the invention in detail reference is had to the accompanying drawings, wherein:

Figure 1 is a diagrammatic elevation partially in section of an apparatus constructed in accordance with the invention and constituting an embodiment thereof;

Figure 2 is an enlarged section taken on the line 2—2 of Figure 1;

Figure 3 is a section in detail showing the bearing mechanism for a rotatable distributing pipe employed in the apparatus illustrated.

Referring now to the drawings it will be seen that the apparatus thus illustrated embodies a heating coil 10 and a cracking still or converter 11. The coil 10 is positioned 70 in a furnace 12, for example, an oil or gas fired furnace, adapted to heat the oil passing through the coil to the temperature desired. The outlet 13 of the coil communicates with the cracking vessel 11 which is preferably 75 provided with insulation 14 but may, if desired, be positioned in a furnace or chamber by which it may be subjected to comparatively moderate heating. Thus, for example, the cracking chamber may be arranged to be heated by means of waste gases from the furnace 12. The oil to be treated is drawn by a pump 15 from a suitable source of supply and charged through the pipe 16 to the heating coil 10. If desired, the oil 80 may, before being introduced to the coil 10, be passed through such exchangers, economizers, preheaters, and the like, as may be desired, the use of which structures is well known in the art and need not be described 85 in detail herein.

If distillation be carried on during the cracking operation, the vapors may be removed by means of a vapor line 17 which may lead to preliminary fractionating or 90 condensing means 18, such as bubble towers, air condensers or the like, by which the products of heavier boiling point than that desired may be condensed. These heavier products may be passed into a line 19 and by means of a pump 20 or other suitable means returned to the pipe 16 and thus discharged into the heating coil 10. A vapor line 21 extends from the separator 18 to a 95 condensing coil 22. The outlet of the condenser leads to a receiving drum 23 wherein 100 105

the condensate may be collected. The cracking vessel may be equipped with a pipe 24 for removing residue.

In the apparatus thus illustrated, a single converter 11 is shown. It is to be understood, however, that a plurality of converters may be employed, if desired, and in fact it is generally preferable to use two or more converters. The apparatus shown is adapted for carrying on the conversion process with simultaneous distillation. If desired, however, the cracking may be carried on in a closed type of converter without distillation, the synthetic crude oil being drawn off for subsequent distillation of the light products formed.

A hollow shaft 25 is rotatably mounted within the still or converter 11 and is adapted to communicate with the pipe 13 which leads from the heating coil 10. As clearly shown in Figure 3, the pipe 13 extends to an opening in the bottom of the still and is welded or otherwise secured to the wall of the still. An annular member 26 is secured to the bottom of the still immediately above the pipe 13 and is provided with a central opening which registers with the pipe 13. The member 26 is preferably equipped with a ground seat for a ring or bearing 27 and the lower end of the rotating pipe 25 is swaged and formed with a ground surface adapted to co-act with a ground surface in the ring 27 so as to form a ball seat for the pipe 25. The several members of the joint are held in position by means of a retaining member 28 which is adapted to engage with the flared end of the pipe 25 and which may be secured in any suitable manner as by being bolted to the bottom of the still. With the ball seat construction it is possible to permit a free rotation of the pipe 25 and at the same time reduce to a minimum leakage in the movable connection between the stationary charging line 13 and the rotating distributing pipe 25. It is apparent, however, that various arrangements may be provided for establishing communication between the stationary pipe and the movable one and it is of course unnecessary to provide a connection which absolutely precludes leakage within the still.

The pipe 25 may be equipped with one or more guide bearings, such, for example, as a bearing indicated at 29, and may be rotated in any convenient manner. Thus the pipe 25 may be connected to a shaft 30, as by means of blind flanges 31, which shaft extends outside of the still through a stuffing box 32 and is driven by a shaft 33 to which it is suitably geared. If desired, the rotatable pipe 25 may be turbine operated, as for instance by means of fluid pressure generated in the process.

The pipe 25 has a plurality of laterally extending branch lines 34 adapted to dis-

charge the heated oil at a plurality of points within the still. In the apparatus illustrated the outer ends of the pipes 34 are connected to discharge pipes or nozzles 35. The distributing pipes or nozzles 35 are preferably rotatably mounted on swivel members 36 adapted to be actuated by the fluid passing through the pipes 34.

In practicing the invention with the apparatus illustrated the oil to be treated is brought to the desired temperature in the coil 10, is then passed through the pipe 13 into the rotatable pipe 25 and is discharged through the several branch lines 34 and spray lines 35 in minutely divided form into the mass of oil in the still. The heated oil from the coil is thus brought into intimate contact with substantially all portions of the mass of oil under conversion with the result that there is ready transfer of heat into the body of oil in the still. At the same time the movement of the several pipes and connections, which constitute the means for spraying the oil into the still, serves to assist in keeping the contents in a state of agitation, which facilitates the heat diffusion and maintenance of the required temperature and also serves to keep the carbon formed in a state of suspension in the oil so that it may readily be drawn off with the liquid when so desired.

It is apparent that many modifications of the invention may be made, for example, instead of providing the movable spraying pipes 35, the shaft 25 may be equipped with a plurality of paddles or propellers which serve to agitate the contents of the still and the oil discharged in sprays or streams at various points throughout the length of the shaft 25. If desired, the oil may be sprayed through orifices formed in the propeller blades or at points adjacent thereto. The blades or propellers may be arranged to impart heat to the oil.

In operating the process, the apparatus is preferably maintained under pressure or at least the coil 10 and cracking chamber 11 are maintained under superatmospheric pressure. In case rotatable spraying mechanism operated by the fluid pressure of the oil discharged into the still, be employed, it is desirable to have the still at a pressure somewhat below that of the coil 10 in order to insure the movement of the rotatable members.

It is preferable to so heat the oil as it passes through the coil 10 that as it is discharged into the pipe 13, it is at a somewhat higher temperature than that desired to be maintained in the cracking vessel 11. By carrying a temperature in the coil outlet of say, 25°, 50° or 100° F. higher than that desired in the cracking vessel 11, the required temperature therein may be readily maintained. For example, the outlet of the

coil 10 may be held at say 800° to 850° F. to maintain a temperature of say 750° to 775° in the cracking still. The temperature differential between the coil and converter will vary considerably with the different factors of operation, such for example, as the size of the apparatus used, whether the converter be insulated or be subjected to moderate heating, and other variable elements.

It may be noted that by carefully regulating the passage of the oil through the coil 10 and the application of heat thereto the oil may be brought to a high cracking 15 temperature in the coil outlet but discharged into the converter 11 before any material decomposition has taken place, and a temperature thus maintained in the converter which, while more or less below that of the 20 coil outlet, is nevertheless adequate for a rapid rate of decomposition. In this way the application of the heat to the metallic walls of the vessel in which the cracking

operation is taking place is obviated, thus preventing the deposition of carbon on the 25 walls of the converter, the carbon formed in the process being maintained in suspension by reason of the sprays of fluid discharged into the vessel and also by reason of the mechanical agitation therein.

Obviously, various modifications of the invention may be effected without departing from the spirit and scope of the invention. The true scope of the invention is defined in the appended claim.

What I claim is:

Apparatus for cracking hydrocarbon oils, comprising a cracking vessel, a hollow shaft mounted therein and in communication with a source of oil supply for said vessel and rotatable spraying means adapted to receive fluid from said shaft and to be actuated by said fluid.

In witness whereof I have hereunto set my hand this 12th day of September, 1923.

WILLIAM S. HADAWAY, JR.
